UNITED STATES PATENT OFFICE.

WILLIAM H. HARGRAVES, OF ALLENTOWN, PENNSYLVANIA.

BUTTONHOLE ATTACHMENT FOR SEWING-MACHINES.

1,184,093.

Specification of Letters Patent. Patented May 23, 1916.

Application filed July 28, 1915. Serial No. 42,292.

To all whom it may concern:

Be it known that I, WILLIAM H. HARGRAVES, a citizen of the United States, residing at Allentown, State of Pennsylvania, have invented certain new and useful Improvements in Buttonhole Attachments for Sewing-Machines; and I do hereby declare the following to be a full, clear, and exact description of the invention, such as will enable others skilled in the art to which it appertains to make and use the same.

My present invention has for its object to provide an improved button-hole attachment for sewing machines, which attachment is also adapted for use in performing certain analogous work, such as tacking pockets, crotches, and other seams.

Generally stated, the invention consists of the novel devices and combinations of devices hereinafter described and defined in the claims.

Particularly, the present invention is designed as an improvement on or refinement of the button-hole attachment disclosed and claimed in Letters Patent of the United States No. 678,397, issued of date, July 16, 1901 to myself, William H. Hargraves, J. S. Heileg, and J. Roberts. Certain features of the present invention, however, are capable of incorporation in so-called button-hole attachments other than that type disclosed in the said prior patent.

In the accompanying drawings which illustrate my invention, like characters indicate like parts throughout the several views.

Referring to the drawings: Figure 1 is a left side elevation of the improved attachment; Fig. 2 is a plan view of the same; Fig. 3 is a bottom plan view of the said attachment; Fig. 4 is a detail in section taken on the line $x^4 x^4$ on Fig. 2; Fig. 5 is a right side elevation of the attachment; Fig. 6 is a bottom plan view of the attachment with some parts removed; Fig. 7 is a vertical section taken approximately on the line $x^7 x^7$ on Fig. 2; Fig. 8 is a detail in elevation with some parts broken away, showing the ring forming a part of the clutch device; and Fig. 9 is a sectional elevation of the lever forming part of the clutch device, taken on the line $x^9 x^9$ on Fig. 2.

A great many of the elements of my present improved attachment as illustrated in the drawings, are identical with corresponding elements of the attachment of the said

prior patent; and such parts are, in the drawings of the present application, indicated by the same letters and powers that are applied thereto in the said patent, while the elements involved in the features of improvement are designated by numerals.

The frame or casing of the attachment comprises a bed a and body portion a^1 and a^2 . The forward end of the casing is provided with a pair of jaws a^3 , one of which is fitted with two jam screws a^4 for clamping the attachment to the presser-foot bar of the sewing machine. In the prior patent, only one jam screw was employed, but I have found that the two jam screws not only more firmly secure the attachment to the said bar but insure better alinement. In the case portion a^1 is journaled a short transverse shaft b , one end of which projects beyond the casing and has fixed thereto a ratchet wheel b^1 . A draft lever b^2 is fulcrumed on the said shaft between the casing and the ratchet wheel b^1 and has a pawl b^3 held by a spring b^4 for engagement with said ratchet wheel.

The forward end of the driving lever b^2 passes through and has sliding connection with an eye b^7 of a link b^8 that is carried by the needle-bar, not shown, but in such manner that the link oscillates with the needle-bar, and hence, imparts a step by step rotary movement to the ratchet wheel b^1 and shaft b .

As a means for imparting vibratory or zigzagging movement to the cloth clamp, a cam wheel c is secured on the shaft b , and this cam is formed with a peripheral zigzag cam groove c^1 that is engaged from below by a roller c^3 of a stitch zigzagging lever 1 . This lever 1 is fulcrumed on a screw bolt c^5 extending through an opening in the frame portion in the casing, and having a threaded lower end on which is screwed a nut c^6 . The nut c^6 not only serves to hold the bolt and lever in position, but works through a slot e^2 in a retaining plate e , and thus holds the said plate with freedom for lateral oscillation.

The cloth clamp f is rigidly secured to the forward end of a longitudinally slotted slide-plate f^1 , which plate is held in position between the bed a and retaining plate e . The main slot in the said plate f^1 affords the required clearness for permitting longitudinal and lateral vibratory movements thereof. The retaining plate e works between later-

ally spaced lugs e^1 on the plate f^1 (see Fig. 3) and partakes of the lateral vibratory movements of the said plate f^1 but does not move longitudinally therewith. On the end 5 of a shaft k in the frame portion a^2 is mounted a friction clutch device for imparting a progressive rotary movement to said shaft. This clutch mechanism comprises a lever h of 10 annular form provided with an opening adapted to fit over the shaft k with some clearance, and a disk g^4 rigidly secured to the end of said shaft. The lever h is mounted on the shaft k between said disk and the frame of the attachment. In an annular 15 groove on the inner side of the disk g^4 is placed a clutch ring formed with two halves g^9 , each of said halves having a portion of one end removed so as to leave a rectangular opening to receive a rectangular lug h^1 on 20 the annular lever h . The said lever has a portion of its periphery cut away, as shown at h^2 , one end of the said opening being formed to provide a seat for a pin i^1 on a two-part clutch actuating slide-bar 2, and 25 the other end of said opening being formed so as to engage one end of a spring h^4 anchored to the frame portion a^2 . The slide-bar 2 rests loosely upon the flanged lower portion of the casing, and at its forward end 30 is provided with a pin i^2 which engages the end or projecting lug of the driving lever b^2 , so that with an upward movement of the needle-bar, the said slide bar 2 will rotate the lever h giving the lug h^1 a twisting motion 35 between the ends of the clutch ring sections g^9 and jamming the same against the peripheral wall of the disk g^4 thereby locking together said sections g^9 to said disk g^4 and thus giving a step of rotary motion to 40 the shaft k . When the pin i^2 is released from lever b^2 on downward movement of the needle-bar, the spring h^4 rotates the lever h in a direction opposite to that in which it is moved by the slide-bar 2; and this 45 reverse movement releases the ring sections g^9 from engagement with the flange of the disk g^4 and permits them to move freely back to initial position without carrying the said disk and shaft k therewith.

50 The two sections of the slide-bar 2 have overlapped serrated surfaces arranged to be adjustably clamped together by a clamp screw 3 that works through a slot 4 in one of the said sections 2 and is screwed 55 into the other. Thus the distance between the studs i^1 and i^2 of the said slide-bar 2 may be varied for the purpose of timing the stroke and taking up lost motion. One of the sections of the said slide-bar 2 is provided 60 with an upwardly projecting stop arm i^3 which is arranged to contact with a stop i^4 in the form of a screw applied to a casing and having an eccentric head portion adapting it to serve as a variable stop for 65 limiting the movement of the slide-bar 2

in the direction in which it is pulled by the spring h^4 .

The intermittent rotary motion of the shaft k is imparted to the cloth clamp plate f^1 through means involving as follows: The rear end of the said cloth clamp plate is provided with a vertical arm l^1 . To a projection a^5 of the casing is pivoted a lever l^2 having a longitudinal slot l^3 in which slot is mounted a screw-ended stud l^4 provided 75 with a collar l^5 and jam-nut l^6 engaging the screw-threaded end of said stud and serving to clamp the same to l^4 in any desired position in the slot l^3 , thereby enabling the extent of the longitudinal feed of the work-clamp plate f^1 to be varied according to the length of the button hole to be sewed. The lever l^2 is pivotally connected at l^8 , to a slotted double-rack pitman m which is engaged by a segmental pinion m^1 secured to 80 the end of the shaft k . The said pinion engages with the respective upper and lower racks of the pitman m at opposite points of its rotation.

From the above description it is obvious 90 that the cloth clamp plate will be moved in opposite directions by the segmental pinion m^1 and the pitman m and that while the pinion turns through the idle parts of the said pitman no endwise movement will be 95 imparted to the cloth clamp plate and clamp. This momentary suspension of the longitudinal feed of the cloth clamp plate occurs at the ends of the button-hole and at such time the cloth clamp plate is shifted 100 to bring the cloth clamp f and work into proper position for sewing the opposite sides of the button-hole, through means which will now be described.

The cam wheel o is fixed to the shaft k 105 and is provided with a peripheral groove having two straight sections and two comparatively short and oblique cam surfaces, all as more fully described in the prior patent above identified. The said cam groove 110 is engaged from below, by a roller p^6 on the stud formed integral with a lever 6 fulcrumed on a screw bolt p^2 extended through an opening in the casing portion a^2 , and in this instance, having a threaded lower end 115 provided with a flanged retaining nut 7, the reduced portion of which nut works in the transverse slot 8 of the retaining plate e .

We will now particularly consider a very 120 important feature of improvement involved in the present attachment, whereby it is not only made possible but an easy matter to vary the adjustment of the devices for controlling the zigzag stitch mechanism and the offsetting stitch movement, from the top or upper part of the attachment and without requiring the attachment to be removed from the sewing machine. As the simplest and most efficient means of accomplishing 125 this result, the cloth clamp slide-plate f^1 is 130

extended considerably at one side of the casing and is provided with a long slot 9, and the levers 1 and 6 are provided with lateral extensions (see particularly Fig. 6) terminating in heads 10 and 11, respectively. The said lever heads 10 and 11 are provided with slots 12 and 13, respectively, that extend parallel to lines drawn through the axes of the pivots and rollers of the respective levers. Adjustably mounted in the slots 12 and 13, respectively, are flanged studs 14 which, by means of clamping nuts 15, are adapted to be secured to coöperating lever heads in different desired adjustments. The lower ends of these studs 14 are provided with swiveled cross-heads 16, the sides of which are flattened so that they slide freely in the slot 9 and in the cloth clamp slide-plate f^1 , but do not rotate therein. These flattened sides of the said cross-heads give long wearing surfaces.

Adjacent to the slots 12 and 13, the lever heads 10 and 11 are preferably graduated, as best shown in Fig. 2, and for coöperating with these graduations, small pointers 17 are secured on the studs 14 between the nuts 15.

As is evident, the farther the cross-heads 16 are secured forward or toward the left, in respect to the drawings, within the slots 12 and 13, the greater will be the lateral oscillation imparted to the slide plate f^1 , and consequently, to the cloth clamp f . It of course, follows from the foregoing description that lateral oscillation imparted to the cloth clamp, through the cam c and lever 1, will impart the zigzag stitch forming movement thereto, while lateral motion imparted to the said cloth clamp through the cam o and lever 6, will shift the cloth clamp so as to throw the stitching from one side to the other of the button-hole. Adjustments for these two different lateral oscillations may, of course, be independently made.

45 A finger-piece or wing 18 is hinged to the outer side of the disk g^4 . This wing, when turned outward, serves as an efficient device by which the said disk may be rotated to cause traveling movements of the cloth clamp, and when it is not in use, it may be turned flatwise against the face of the said disk, thereby lessening the space required in packing the device.

What I claim is:

55 1. In a sewing machine attachment, the combination with a casing, cams mounted therein and means for rotating said cams, of a cloth clamp slide, a cloth clamp carried by said slide, means for imparting end-
wise back-and-forth motion to said slide, levers pivoted to said casing and operated by the said cams, said levers having arms extended beyond the side of said casing, and independent adjustable throw connections
60 between the projected ends of said lever

arms and the extended side of said slide, exposed for adjustment above said slide, and permitting the above noted endwise back and forth movements of said slide.

2. In a sewing machine attachment, the combination with a casing, cams mounted therein and means for rotating said cams, of a cloth clamp slide having a portion projected at one side of said casing and provided with a longitudinal cross head slot, levers pivoted to said casing and operated by said cams, said levers having arms extended beyond the side of said casing and terminating in slotted heads, and cross-heads adjustably connected to the slotted heads of said lever arms and working in the cross-head slot of said slide.

3. In a sewing machine attachment, the combination with a casing, cams mounted therein and means for rotating said cams, of a cloth clamp slide having a portion projected at one side of said casing and provided with a longitudinal cross-head slot, levers pivoted to said casing and operated by said cams, said levers having arms extended beyond the side of said casing and terminating in slotted heads, and cross-heads adjustably connected to the slotted heads of said lever arms and working in the cross-head slot of said slide, and means for adjustably connecting said cross-heads to the said lever arm heads comprising nuts exposed above the same so that adjustments may be made while the attachment is in working position.

4. In a sewing machine attachment, the combination with a casing, cams mounted therein and means for rotating said cams, of a cloth clamp slide having a portion projected at one side of said casing and provided with a longitudinal cross-head slot, levers pivoted to said casing and operated by said cams, said levers having arms extended beyond the side of said casing and terminating in slotted heads, cross-heads adjustably connected to the slotted heads of said lever arms and working in the cross-head slot of said slide, means for adjustably connecting said cross-heads to the said lever arm heads comprising nuts exposed above the same so that adjustments may be made while the attachment is in working position, and the said lever arm heads having graduations adjacent to their slots for indicating different adjustments.

5. In a sewing machine attachment, the combination with a casing, of two rotary cams mounted therein, a ratchet wheel rotatable with the first cam, a pawl-equipped driving lever coöperating with said ratchet wheel and adapted to be vibrated by the needle-bar of a sewing machine, connections operated by said cams for imparting different lateral vibrations to said slide, means whereby rotation of the second cam will impart a

1 back-and-forth endwise movement to said slide, a rotary clutch for directly imparting rotation to said second cam, and a longitudinally adjustable slide bar receiving 5 endwise movement from said driving lever and imparting step by step rotary movement to said clutch.

6. In a sewing machine attachment, the combination with a casing, of two rotary 10 cams mounted therein, a ratchet wheel rotatable with the first cam, a pawl-equipped driving lever coöperating with said ratchet wheel and adapted to be vibrated by the needle-bar of a sewing machine, connections 15 operated by said cams for imparting different lateral vibrations to said slide, means whereby rotation of the second cam will impart a back-and-forth endwise movement to said slide, a rotary clutch for directly imparting rotation to said second cam, a longitudinally adjustable slide bar receiving endwise movement from said driving lever and imparting step by step rotary movement to 20 said clutch, one of the sections of said slide-

bar having a projecting stop lug, and a relatively fixed stop, and a spring operative on said slide-bar and normally holding the stop lug thereof engaged with said relatively fixed stop.

7. In a sewing machine attachment, the 25 combination with a cloth clamp and a slide carrying the same, of two cams with connections for imparting different lateral vibrations to said slide, a driving lever, a clutch device comprising clutch members 30 connecting said lever to one of said cams, an operating crank or hand piece pivoted to one of the clutch members for folding movements toward and from the same, and connections from the cam operated by said 35 clutch, for imparting endwise traveling movements to said slide and cloth clamp.

In testimony whereof I affix my signature in presence of two witnesses.

WILLIAM H. HARGRAVES.
